UNITED STATES PATENT OFFICE.

FRANK N. REEVES, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 28, 1922. Serial No. 609,377.

To all whom it may concern:

Be it known that I, FRANK N. REEVES, a citizen of the United States of America, residing at Newark, in the county of Essex 5 and State of New Jersey, have invented certain new and useful Improvements in Telephone-Exchange Systems, of which the following is a full, clear, concise, and exact description.

10 This invention relates to telephone exchange systems, and more particularly, to a testing circuit for testing the apparatus of an operator's position.

In a telephone exchange system during 15 the period when the exchange is being changed from a manual to an automatic operating basis, there are certain offices which are equipped with machine switching apparatus and function for calls local 20 thereto on a full mechanical basis and other offices which are equipped with regular manual equipment. If the offices of the exchange area are widely separated, it is not feasible because of the expense involved, 25 to extend direct trunks between each and every office in the area and, therefore, in order to enable a subscriber in an office to obtain a connection with any other subscriber in the exchange area, tandem switch- 30 ing offices are provided at convenient points in the exchange area from which trunks radiate to all offices adjacent thereto. Thus, for example, if a subscriber in one manual office desires to obtain a connection with a 35 subscriber's line terminating in another manual office remote therefrom, the "A" operator of the office in which the calling line terminates will first obtain a connection with the tandem switching office, where- 40 upon the "B" or cordless operator of such tandem office will semi-automatically extend the connection to the manual office in which the desired line terminates, where the terminating operator will complete the connection. 45

Under this method of operation, the operator at the tandem office receives the designation of the desired line over a call circuit from the originating or "A" operator 50 and writes up the designation upon her keyboard. The office sender associated with her position then proceeds to cause the operation of selector switches to select an idle trunk extending to the office in which the desired line terminates and to cause the

line designation to be displayed upon a call indicator associated with the terminating operator's position in the selected office.

In order that at all times the apparatus at the "B" or cordless operator's position 60 of the tandem switching office shall be maintained at the highest possible degree of efficiency so that the line designations shall be accurately displayed at the terminating office, it is desirable that means be provided for testing the accuracy with which the line designations which are recorded upon the keyboard of any cordless operator's position are transferred over outgoing 65 trunks. 70

It is, therefore, the object of the present invention to provide a testing circuit which may be associated with the apparatus of an operator's position for testing the accuracy 75 with which such apparatus functions in transferring line designations.

A further object of the invention is to provide an indicator observable from any point in an operating room for displaying 80 designations of lines.

In a tandem switching office of the character above described, desks are provided in the operating room upon which the "B" or cordless positions are located. In accordance with this invention one or more 85 indicating devices are conveniently positioned in the operating room, each comprising lamp boxes which may be observed from any operator's position. The lamp boxes are designed to display any line 90 designation which the operator at any position may record on the keyboard of her position. These indicating devices are accessible from any operator's position through a testing trunk which terminates 95 either in the district or office selector multiples. The district or office selectors are directed to the terminals of this trunk through the depression of office coordinate keys of the operators' keyboard. In ad- 100

dition, each operator's position is provided with a jack for enabling the operator to connect her headset with the test trunk if she desires to conduct a talking test. Thus, if it is desired to test the apparatus of any operator's position, the proper coordinate keys of the operator's keyboard are depressed for causing a district or office selector to select the test line terminating in the indicating devices, and numerical keys cor- 110

respondings to the number with which the position apparatus is to be tested are then depressed. If the indicating device thereupon displays correctly the number recorded, it is then known that the operator's sending apparatus has functioned accurately. In this manner, the position may be tested with a series of numbers which will fully demonstrate its ability to operate accurately.

10 It is thought that the features of the invention will be best understood from a consideration of the following description taken in connection with the accompanying drawings.

15 Fig. 1 shows diagrammatically a trunk incoming from a manual office terminating in a district selector at a cordless operator's position of a tandem switching office, a keyboard and sender at such operator's position 20 and the outgoing end of a test trunk accessible to all cordless district selectors of the office.

Fig. 2 shows controlling circuits of an indicating device in which the test trunk of 25 Fig. 1 terminates.

Fig. 3 shows lamp boxes of the indicating device and register controlling relays therefor.

Fig. 4 shows in detail the arrangement of 30 lamps in one of the lamp boxes of Fig. 3 and the circuits of the controlling sequence switch associated therewith.

Fig. 5 shows in a diagrammatic manner 35 the apparatus and circuits involved in extending a connection from a calling subscriber's line in one manual office through the cordless position of a tandem office to a subscriber's line terminating in a second manual office, or to the test indicator forming 40 the subject matter of this invention.

Fig. 1 should be placed above Fig. 2, and Fig. 3 should be placed to the right of Fig. 2 with the lines extending to the adjoining margins of the figures in alignment for a 45 consideration of the circuits as an entity. The apparatus of the cordless operator's position, illustrated in Fig. 1, comprises a trunk circuit 104 terminating at its outgoing end in a jack at an "A" operator's position 50 in an originating office and terminating at the tandem switching office in the brushes of a panel-type district selector 150, a keyboard 100, a sender 101, a sender selector 103 and a trunk finder 102 for associating 55 the keyboard 100 with an idle sender 101 and with the trunk circuit 104. This apparatus has not been fully disclosed herein since it enters only incidentally into the disclosure of this invention. For a full disclosure 60 thereof, reference may be had to Patent No. 1,501,871, issued to F. A. Stearn, July 15, 1924.

The circuits and apparatus of Figs. 2 and 65 3 are of substantially the same type as disclosed in the Patent No. 1,464,084, issued to

A. E. Lundell and E. H. Clark, August 7, 1923, differing therefrom only in the employment of indicating lamps arranged in the manner shown in the patent to F. N. Reeves, 1,337,482, issued April 20, 1920. 70 Four groups of lamp relays are shown in Fig. 3, each group controlling an indicator of the type disclosed in the aforesaid patent to F. N. Reeves and as disclosed in detail in Fig. 4. In order to simplify the disclosure the sequence switch and indicator associated with each group of register relays have not been disclosed in Fig. 3, these sequence switches being represented herein by the rectangles 300, 301, 302 and 303 and the indicators by the rectangles 304, 305, 306 and 307. In the consideration of the circuits of Fig. 3, the circuits of Fig. 4, are, therefore, to be substituted for the rectangles shown in Fig. 3. 80

85 Each of the indicators of Fig. 3 comprises a lamp box having transparent panels of the shape shown in dotted lines in Fig. 4 and seven groups of lamps, a group of lamps positioned behind each of said panels. 90 These panels have been designated as 1-1, 2-2, 3-3, etc., in Fig. 4. Thus, to display the digits 0 to 9, inclusive, the lamps behind the seven panels are lighted through the setting of the associated sequence switch in the 95 following combinations:

Digit.	Sequence switch position.	Lamps.						
		1	2	3	4	5	6	7
0	2							
1	3							
2	4	1						
3	5	1						
4	6		2	3				
5	7	1	2					
6	8	1	2		4	5		
7	9	1		3				
8	10	1	2	3	4	5	6	7
9	11	1	2	3	4		6	7

In Fig. 3 the indicators have been shown as they would appear in displaying the 110 designation 3578 although the controlling circuits are disclosed as in their normal position.

The sequence switches 110 and 410 may be of the same structure as disclosed in Patent 1,127,808, issued to J. N. Reynolds and C. F. Baldwin, February 9, 1915. Only a portion of the cams controlled by the switch 110 and a portion of the controlling circuits thereof have been disclosed in Fig. 1. For a full disclosure of the circuits thereof, reference may be had to the patent to F. A. Stearn hereinbefore referred to. 115

The apparatus employed and the manner in which it functions having now been 120 briefly described, it is thought that the invention will be better understood from a more detailed consideration of the manner in which the circuits are employed. Two 125 types of tests may be conducted employing 130

the apparatus employed herein. First a test of the "B" or cordless operator's apparatus conducted entirely from such operator's position and in connection with 5 which no talking test is made, a second test conducted in conjunction with an originating "A" operator's position in connection with which test a talking connection is established between the "A" position and the 10 "B" position under test. A test of the first character will first be considered, it being assumed that coordinate office keys of the keyboard 100 are depressed for routing the test call to the terminals of the test trunk 112 over the brushes of the district selector 150 and, that keys are depressed for displaying the designation of line 3578—M upon the indicators of Fig. 3. It will be further assumed that for the purpose of making the 15 test the trunk circuit 104 terminating in district selector 150 is assigned for use by the "B" operator.

In the manner fully set forth in the aforesaid patent to F. A. Stearn upon the assignment of the trunk for use, the operator's keyboard 100 is connected by the trunk hunting switch 102 with the trunk 104 and an idle sender 101 is associated therewith by the sender selector 103. Thereupon, the 20 registers of the sender are set in accordance with the office and numerical designations recorded upon the keyboard 100 and the sender proceeds to function to set the brushes of the district selector 150 upon the 25 terminals of the test trunk 112. As soon as the selector switch 150 has positioned its brushes upon the terminals of trunk 112, the sequence switch 110 associated with the district selector advances to the selection-beyond 30 position 11. The selected trunk 112 is now maintained busy to all other selector switches having access thereto by ground potential placed upon the multiples of the test terminal 107, over brush 111 and the right 35 contacts of cam 113.

With sequence switch 110 in position 11, a circuit is now established from battery, right winding of relay 114, right winding of coil 115, inner right armature and back contact of relay 116, upper armature and back contact of relay 117, terminal 105 and brush 108, contact of cam 118 (11), wiper 119 of the trunk finding switch 102, wiper 120 of the sender selector switch 103, the controlling 40 circuit of sender 101, wiper 121, wiper 122, lower contact of cam 123 (11), brush 109, terminal 106, lower armature and back contact of relay 117, inner left armature and back contact of relay 116, left winding of coil 115 to ground, through the 45 left winding of relay 114. Relay 114 energizes in this circuit closing a circuit for relay 124 from ground at the armature and back contact of relay 200, conductor 201, armature and contact of relay 114, left wind-

ing of relay 124, outer armature and back contact of relay 125, conductor 126 to battery through the winding of relay 202. Relays 124 and 202 energize in this circuit, relay 124 closing a locking circuit for itself 50 from battery through the winding of relay 202, conductor 126, the outer armature and back contact of relay 125, both windings of relay 124, right armature and contact thereof, outer left armature and back contact of relay 116 to ground at the lower contact of cam 113. Relay 124 also establishes a circuit for relay 117 which may be traced from battery through the winding of relay 117, left armature and contact of relay 124, conductor 127 to ground through the winding of relay 200. With relay 117 energized the circuit previously traced through the winding of relay 114 is opened at the armatures and back contacts of relay 117 and relay 114 55 thereupon retracts its armature opening the initial energizing circuit of relay 124.

Relay 202, upon energizing in series with relay 124, closes an obvious circuit for relay 203, which, at its armatures and back contacts removes ground from the conductors 204, 205, 206 and 207 leading through restoring contacts of cams on the sequence switches associated with the several indicators. Relay 202 at its inner right armature 60 and contact closes an obvious circuit for relay 208, and, at its left armature and contact connects ground to conductor 209 for furnishing a locking ground for certain of the switching relays of Fig. 2. Relay 208, upon energizing, supplies a locking ground to the remaining switching relays of Fig. 2 and to the register relays of Fig. 3 and an operating ground to the armatures of control relays 210, 211 and 212, over conductor 216. 65

With relay 117 operated, a fundamental controlling circuit is established from the sender 101 through the windings of control relays 210, 211 and 212 which may be traced as previously described from the sender to the armatures of relay 117 and from thence as follows: upper armature and front contact of relay 117, conductor 128, inner right armature and back contact of switching relay 213, conductor 214, winding of positively polarized relay 212, winding of negatively polarized relay 211, winding of marginal relay 210, conductor 215, inner left armature and back contact of switching relay 213, conductor 129 to the lower armature and front contact of relay 117. The circuits are now in condition to receive the first set of code impulses corresponding to the stations designation of the number recorded on the keyboard. Each set of code impulses in accordance with the well-known standard practice consists of a maximum of four impulses: The first and third impulses of each set are always either weak positive or are entirely omitted and the second and fourth 70 75 80 85 90 95 100 105 110 115 120 125 130

impulses are either weak or strong negative current.

It has been assumed that the "B" operator has recorded the designation 3578—M upon her keyboard. Therefore, the first impulses now transmitted from the sender 101 through the winding of relays 210, 211 and 212 for registering the stations designation M comprise a light negative impulse followed by a heavy negative impulse. In response to the first light negative impulse the negatively polarized relay 211 energizes, closing a circuit from ground on conductor 216, through the armature and contact of relay 211, conductor 227, outer left armature and normal contact of switching relay 213, conductor 228, left armature and back contact of relay 230, winding of relay 220 to battery through the left winding of relay 230. Relay 220 energizes in this circuit, but relay 230 does not receive sufficient current to cause its energization. Relay 220, upon energizing, closes a circuit from battery through the left winding of relay 230, the winding of relay 220, the right winding of relay 230, the inner right armature and contact of relay 220 to ground on conductor 216. Relay 230, however, does not energize at this time since its right winding is shunted through the contact of relay 211. Relay 220 at its outer right armature and front contact closes a circuit for the switching relay 218 which may be traced from battery through the winding of relay 218, the outer left armature and back contact of relay 217, the outer right armature and contact of relay 220 to ground on conductor 216. Relay 218, upon attracting its armatures, establishes a locking circuit for itself from battery, through its winding, the winding of relay 217, the inner right armature and front contact of relay 218 to ground on conductor 216. Relay 217, however, does not energize at this time since its winding is shunted by a direct path to ground through the armature and contact of relay 220. As soon, however, as relay 211 de-energizes following the transmission of the first impulse of the station's code and removes the shunt from around the winding of relay 230, relay 230 energizes in series with relay 220.

In response to the second impulse of strong negative current, negatively polarized relay 211 again energizes and in addition marginal relay 210 also energizes. Relay 211 upon attracting its armature, closes a circuit from battery, through the left winding of relay 230, left armature and front contact of this relay, conductor 228, outer left armature and normal contact of relay 213, conductor 227, armature and contact of relay 211 to ground on conductor 216. This direct circuit to ground shunts the winding of relay 220 causing it to deener-

gize and release its armatures. Upon the release of its outer right armature, the shunt around the winding of switching relay 217 is opened, but this relay is still maintained shunted over the inner right armature and contact of relay 230 to ground on conductor 216. Relay 210, upon energizing, closes a circuit from ground on conductor 216, over the armature and contact of relay 210, conductor 231, the outer right armature and front contact of relay 230, the inner left armature and back contact of relay 217, conductor 232 to battery through the left winding of stations register relay 324. Relay 324, upon energizing in this circuit, establishes a locking circuit for itself from battery through both of its windings in series, its right armature and contact to ground on conductor 216. Upon the termination of the second, strong negative impulse of the stations code, relays 210 and 211 deenergize, relay 211 opening the circuit through the left winding of relay 230. Relay 220 being at this time deenergized, no other circuit exists for relay 230, and, consequently relay 230 becomes deenergized. When relay 230 releases its armatures, the shunt around the winding of switching relay 217 is removed and this relay energizes in the locking circuit of relay 218. It will be noted that only one stations relay 324 has been operated.

Since it has been assumed that the thousands digit of the line designation is 3, the thousands code will comprise a positive impulse followed by a weak negative impulse and a strong negative impulse. In response to the first positive impulse, the positively polarized relay 212 energizes, closing a circuit from ground on conductor 216, through the armature and contact of relay 212, conductor 253, the left armature and back contact of relay 220, the left armature and front contact of switching relay 218, the left armature and back contact of switching relay 222, conductor 234 to battery through the left winding of thousands register relay 311. Relay 311, upon energizing, closes a locking circuit for itself extending from battery, through both of its windings in series, its inner right armature and front contact to ground on conductor 216. Upon the termination of the first positive impulse, relay 212 deenergizes. In response to the second impulse of weak negative current, the negatively polarized relay 211 energizes, closing the previously traced circuit through the winding of relay 220 and the left winding of relay 230. Relay 220 now energizes preparing an energizing circuit for relay 230 as previously described and establishing a circuit for the switching relay 222, from battery, through the winding of relay 222, the outer left armature and back contact of relay 221, the outer left armature and front contact of

relay 217, outer right armature and contact of relay 220 to ground on conductor 216. Relay 222, upon energizing, closes a locking circuit for itself extending from battery through its winding, the winding of relay 221, the inner right armature and front contact of relay 222 to ground on conductor 216, but relay 221 being shunted at this time at the contact of relay 220 does not energize in this locking circuit. When the second negative impulse ceases, relay 211 deenergizes, opening the shunt around the right winding of relay 230, whereupon this relay energizes in series with relay 220.

5 In response to the third impulse of strong negative current, the negatively polarized relay 211 and marginal relay 210 both energize, relay 211 establishing the previously traced circuit from ground directly through the left winding of relay 230 thereby shunting the winding of relay 220 and causing the deenergization thereof. Relay 210, upon energizing, closes a circuit from ground on conductor 216, through the armature and contact of relay 210, conductor 231, the outer right armature and front contact of relay 230, the inner left armature and front contact of relay 217, the inner left armature and back contact of relay 221, conductor 235 to battery through the left winding of thousands register relay 308. Relay 308, upon energizing, closes a locking circuit for itself extending from battery through both of its windings in series and the contact of its right armature to ground on conductor 216. Upon the termination of the third impulse of the thousands code, relays 210 and 211 deenergizes, relay 211 opening the holding circuit of relay 230 permitting it to retract its armatures. Since at this time both relays 220 and 230 are deenergized, the shunt around the winding of switching relay 221 is opened and relay 221 energizes in the holding circuit of relay 222. The thousands register relays 308 and 311 have now been energized and locked.

10 It having been assumed that the hundreds digit of the line designation is 5, the hundreds code of impulses will comprise a light negative impulse followed by a strong negative impulse. In response to the first impulse of light negative current, relay 211 energizes closing the previously traced circuit through the winding of relay 220 and the left winding of relay 230. Relay 220 energizes in this circuit, closing a holding circuit for itself through both windings of relay 230, relay 230, however, remaining deenergized at this time. At its outer right armature and contact, relay 220 establishes a circuit for switching relay 224 which may be traced from battery through the winding of relay 224, the outer left armature and back contact of relay 223, the outer left armatures and front contacts of relays 221

15 and 217, the outer right armature and contact of relay 220 to ground on conductor 216. Relay 224, upon energizing, now establishes a holding circuit for itself extending from battery through its winding, the winding of switching relay 223, the inner right armature and front contact of relay 224 to ground on conductor 209. Upon the cessation of the first negative impulse of current, the shunt around the right winding of relay 230 is removed at the armature and contact of relay 211 and relay 230 energizes in series with relay 220.

20 In response to the second impulse of strong negative current, relays 210 and 211 energize, relay 211 closing the previously traced circuit from ground directly through the left winding of relay 230 thereby shunting the winding of relay 220 and causing the deenergization thereof. Relay 210, upon energizing, closes a circuit from ground on conductor 216, through the armature and contact of relay 210, conductor 231, the outer right armature and front contact of relay 230, the inner left armatures and front contacts of switching relays 217 and 221, the inner left armature and back contact of switching relay 223, conductor 236 to battery through the left winding of hundreds register relay 312. Relay 312, upon energizing in this circuit, closes a locking circuit for itself extending from battery through both of its windings in series, its right armature and contact to ground on conductor 216. Upon the cessation of the second and last of the hundreds code of impulses, relays 210 and 211 become deenergized, relay 211 opening the circuit of relay 230 causing the latter relay to release its armatures. Since at this time both relays 220 and 230 are deenergized, the shunt around the winding of switching relay 223 is removed and this relay energizes in the holding circuit of relay 224. Only one hundreds register relay 312, has been operated in response to the hundreds code of impulses.

25 For registering the tens digit 7, the sender 101 transmits a code of impulses comprising two strong negative impulses. In response to the first strong negative impulse the negatively polarized relay 211 and marginal relay 210 energize. Relay 211, upon energizing, closes the previously traced circuit through the winding of relay 220 and the left winding of relay 230, relay 220 closing a holding circuit for itself through both windings of relay 230. Relay 230, however, being shunted at this time at the contact of relay 211 does not energize. Relay 220 also closes a circuit for the switching relay 226 which may be traced from battery through the winding of relay 226, the outer left armature and back contact of relay 225, the outer left armatures and front

contacts of relays 223, 221 and 217, the outer right armature of relay 220 to ground on conductor 216. Relay 226, upon energizing, closes a locking circuit for itself 5 extending from battery, through its winding, the winding of relay 225, the inner right armature and contact of relay 226 to ground on conductor 209. Relay 210, upon energizing, closes a circuit which may be 10 traced from ground on conductor 216, the armature and contact of relay 210, conductor 231, the outer right armature and back contact of relay 230, the right armatures and front contacts of relays 217, 221 and 223, the inner right armature and back contact of relay 225, conductor 237 to battery 15 through the left winding of tens register relay 318. Relay 318, upon energizing in this circuit, closes a locking circuit for itself from battery, through both of its 20 windings in series, its inner right armature and front contact to ground on conductor 216. Upon the cessation of the first impulse of the tens code, relays 210 and 211 deenergize, relay 211 removing the shunt from 25 around the right winding of relay 230 permitting this relay to energize in series with relay 220.

In response to the second strong negative 30 impulse of the tens code, relays 210 and 211 again energize, relay 211 closing a circuit from ground directly through the left winding of relay 230 in shunt of the winding of relay 220, causing the deenergization of this latter relay. Relay 210, upon energizing, establishes a circuit from ground on conductor 216, through the armature and contact of relay 210, conductor 231, the outer right armature and front contact of relay 230, the inner left armatures and front contacts of switching relays 217, 221 and 223, the outer right armature and back contact of relay 225, conductor 238 to battery, through the left winding of tens register relay 316. Relay 316, upon energizing, closes a locking 40 circuit for itself from battery through both of its windings in series, its right armature and contact to ground on conductor 216. Upon the cessation of the second negative 45 impulse, relays 210 and 211 deenergize, relay 211 opening the holding circuit of relay 230 whereupon relay 230 releases its armatures. Since at this time both relays 220 and 230 are deenergized, the shunt about 50 the winding of relay 225 is opened and this relay energizes in the holding circuit of relay 226. Tens register relays 316 and 318 have now been operated in response to the tens code of impulses.

60 Since it has been assumed that the units digit of the line designation is 8, the sender 101 transmits a code of impulses comprising a positive impulse followed by two strong negative impulses. In response to 65 the first positive impulse, the positively

polarized relay 212 energizes, closing a circuit from ground on conductor 216, the armature and contact of relay 212, conductor 233, the left armature and back contact of relay 220, the left armatures and front contacts of relays 218 and 222, the outer left armatures and front contacts of relays 224 and 226, conductor 239 to battery through the left winding of units register relay 323. Relay 323, upon energizing, 70 locks from battery through both of its windings in series, its inner right armature and contact to ground on conductor 216. Upon the cessation of the first positive impulse, relay 212 deenergizes. 80

In response to the second impulse of strong negative current, relays 210 and 211 energize, relay 211 closing the previously traced circuit through the winding of relay 220 and the left winding of relay 230. Relay 220, upon energizing, closes a holding circuit for itself through both of the windings of relay 230, and a circuit for the switching relay 219, which latter circuit may be traced from battery, through the 90 winding of relay 219, the outer left armatures and front contacts of switching relays 225, 223, 221 and 217, the outer right armature and contact of relay 220 to ground on conductor 216. Relay 219 now closes a 95 holding circuit for itself extending from battery through its winding, the winding of relay 213, the inner right armature and contact of relay 219 to ground on conductor 209. Relay 210, upon energizing, closes a circuit from ground on conductor 216, the armature and contact of relay 210, conductor 231, the outer right armature and back contact of relay 230, the right armatures and front contacts of relays 217, 221 and 223, the inner right armature and front contact of relay 225, conductor 240, to battery through the left winding of units register relay 322. Relay 322, upon energizing 100 in this circuit locks from battery through both of its windings and the front contact of its inner right armature to ground on conductor 216. Upon the termination of this impulse, relays 210 and 211 deenergize, relay 211 removing the shunt from the right 115 winding of relay 230 whereupon relay 230 energizes in series with relay 220.

In response to the third impulse of strong negative current, relays 210 and 211 again energize, relay 211 closing a circuit from 120 ground directly through the left winding of relay 230 shunting down relay 220 which thereupon deenergizes. Relay 210, upon energizing, closes a circuit from ground on conductor 216 through the armature and contact of relay 210, conductor 231, the outer right armature and front contact of relay 230, the inner left armatures and front contacts of relays 217, 221, 223 and 225, conductor 241 to battery through the 125 130

- left winding of units register relay 320. Relay 320 now locks from battery through both of its windings in series and the contact of its right armature to ground on conductor 216. Upon the termination of this impulse, relays 210 and 211 deenergize, relay 211 opening the circuit of relay 230 causing it to release its armatures. Since at this time the shunt about the winding of switching relay 213 is opened at contacts of both relays 220 and 230, relay 213 energizes in the locking circuit of relay 219. The impulses of the units code have now been transmitted and units register relays 320, 322 and 323 are locked energized. The entire designation of the number recorded upon the keyboard 100 at the "B" operator's position has now been transferred to the register relays of the test indicator.
- At the time a circuit was closed for the switching relay 219 during the transmission of the last or units series of code impulses, a circuit was also closed in parallel therewith through the winding of relay 242 to battery. Relay 242, upon energizing, closes a holding circuit for itself extending from battery through its own winding, winding of relay 243, the inner armature and contact of relay 242, conductor 244, the outer right armature and contact of relay 219 to ground at the inner left armature and contact of relay 226. Relay 243, however, does not energize in this holding circuit since its winding is shunted by direct ground through the armatures and contacts of relays 220 and 230 as long as either of the latter relays are energized. Relays 242 at its outer left armature and contact establishes a circuit for relay 328 preparatory to lighting the selected stations lamp. When the last code impulse of the units series has terminated, relays 220 and 230 both become deenergized and relay 243 thereupon energizes in the holding circuit of relay 242.
- As soon as relay 243 operates, a circuit is closed for relay 246 which may be traced from battery through the winding of relay 246, conductor 245, to ground at the armature and contact of relay 243. With relays 242 and 246 energized circuits are now effective for causing the display of the entire line designation.
- It will be recalled that in response to the thousands series of code impulses, register relays 308 and 311 were operated, relays 309 and 310 remaining in their unoperated positions. A circuit is now closed from ground through the uppermost armature and contact of relay 246, conductor 247, the left armature and front contact of relay 308, the alternate contacts associated with the outer left armature of relay 311, the inner left armature and back contact of relay 310, conductor 330, thence referring to Fig. 4 through the lower right contact of a cam corresponding to cam 412 (1 to 4) to battery through the magnet winding of sequence switch 300. The sequence switch is now advanced into position 5 where it is arrested since its driving circuit is opened at the lower right contact of the cam corresponding to cam 412 and no other driving circuit exists therefor.
- With sequence switch 300 in position 5, the following lamp circuits are closed: ground, lower contact of the cam corresponding to cam 415 (4 to 5), lamps 1-1 to battery; ground, upper right contact of said cam (2 to 6), lamps 3-3 to battery; ground lower right contact of the cam corresponding to cam 416 (4 to 8), lamps 4-4 to battery; ground, upper right contact of the cam corresponding to cam 416 (5 to 11), lamps 6-6 to battery; ground, upper left contact of the cam corresponding to cam 416 (4 to 5), lamps 7-7 to battery. Lamps 1-1, 3-3, 4-4, 6-6 and 7-7 are now lighted over the above traced circuits and in combination display the digit 3 on the thousands indicator 304.
- As a result of the transmission of the hundreds code of impulses register relay 312 was operated, relays 313, 314 and 315 being unoperated. A circuit is now effective for advancing the sequence switch of the hundreds indicator 305, which may be traced from ground through the armature contact 248 of relay 246, conductor 250, the left armature and front contact of relay 312, the outer left armature and back contact of relay 315, the outer right armatures and back contacts of relays 314 and 313, conductor 331, thence referring to Fig. 4, through the lower right contact of a cam corresponding to cam 413 (1 to 6), to battery, through the magnet winding of sequence switch 301. The sequence switch designated by the rectangle 301 associated with the hundreds indicator 305 thereupon advances into position 7. With this sequence switch in position 7, circuits are established for the lamps of the hundreds indicator as follows, reference being had to Fig. 4: ground, lower contact of the cam corresponding to cam 415 (7 to 11), lamps 1-1, to battery; ground, upper left contact of the cam corresponding to cam 415 (6 to 8), lamps 2-2 to battery; ground, lower right contact of the cam corresponding to cam 416 (4 to 8), lamps 4-4 to battery; ground, upper right contact of the cam corresponding to cam 416 (5 to 11), lamps 6-6 to battery; ground, upper left contact of the cam corresponding to cam 416 (7 to 8), lamps 7-7 to battery. Lamps 1-1, 2-2, 4-4, 6-6 and 7-7 are thus lighted for displaying the digit 5 on the hundreds indicator 305.
- In response to the tens code of impulses, the tens register relays 316 and 318 were operated, relays 317 and 319 remaining un-

operated. A circuit is, therefore, effective which may be traced from ground through the armature contact 249 of relay 246, conductor 251, the left armature and front contact of relay 316, the outer left armature and back contact of relay 319, the outer right armature and front contact of relay 318, conductor 332, thence, referring to Fig. 4, through the upper left contact of the cam of sequence switch 302 corresponding to cam 413 (1 to 8) to battery through the magnet winding of sequence switch 302 corresponding to switch 410. This sequence switch is thereupon driven from its normal position 10 through position 8 and comes to rest in position 9. With the sequence switch in position 9, the following lamp circuits are closed: ground, the lower contact of the cam of switch 302 corresponding to cam 415 (7 to 11), lamps 1—1 to battery; ground, the upper right contact of the cam corresponding to cam 415 (9 to 11), lamps 3—3 to battery; ground, the upper right contact of the cam corresponding to cam 416 (5 to 11), lamps 6—6 to battery. Lamps 1—1, 3—3 and 6—6 are now lighted displaying the digit 7 on the tens indicator 306.

As will be recalled, the units register relays 320, 322 and 323 were energized in response to the units code of impulses and, therefore, upon the energization of relay 246, a circuit is effective for advancing the sequence switch designated by rectangle 303 similar to switch 410 shown in detail in Fig. 4, from its normal position. This circuit may be traced from ground through the lowermost armature contact of relay 246, conductor 252, the left armature and front contact of relay 320, the alternate contacts 30 associated with the outer left armature of relay 323, the inner left armature and front contact of relay 322, the outer left armature and back contact of relay 321, conductor 333, thence, referring to Fig. 4, through the lower contact of the cam of switch 303 corresponding to cam 414 (1 to 9), to battery through the magnet winding corresponding to the winding of sequence switch 410. The sequence switch now advances from its normal position through position 9 and comes to rest in position 10. With the sequence switch in position 10, the following circuits are closed for the lamps of the units indicator: Ground, the lower contact of the cam of switch 303 corresponding to cam 415 (7 to 11), lamps 1—1 to battery; ground, the upper right contact of the cam corresponding to cam 415 (9 to 11), lamps 3—3 to battery; ground, the upper left contact of this cam (10 to 11), lamps 2—2 to battery; ground, the lower right contact of the cam corresponding to cam 416 (10 to 11), lamps 4—4 to battery; ground, the upper right contact of this cam (5 to 11), lamps 6—6 to battery; ground, the lower left contact

of this cam (10), lamps 5—5 to battery; ground, the upper left contact of this cam (10 to 11), lamps 7—7 to battery. All of the lamps of the units indicator are thus lighted displaying the units digit 8 upon the 70 units indicator 307.

A circuit is also closed at this time from ground, through the inner left armature and contact of switching relay 224, conductor 253, the left armature and front contact of stations register relay 324, it being recalled that this register relay was the only stations relay energized in response to the stations code of impulses, thence over conductor 334, through the M stations lamps 329, the outer right armature and contact of relay 328, to battery. The entire designation 3578—M which the "B" operator recorded upon her keyboard 100 is now displayed upon the indicators and from the displayed number, the operator may check the accuracy with which her position apparatus has functioned. 80

Having ascertained if the line designation has been correctly displayed, the operator may proceed to release the apparatus by depressing the disconnect key 130 associated with her position. Upon the depression of key 130, a circuit is established from battery through the winding of relay 132, the contact of cam 131 (2 to 17), to ground at key 130. Relay 132, upon energizing in this circuit established a circuit for advancing sequence switch 110 out of position 12 to which it was advanced following the termination of the transmission of code impulses. The circuit of sequence switch 110 may be traced from battery, through the magnet winding of sequence switch 110, contact of cam 133 (12 to 17), the armature and contact of relay 132, the upper left contact of cam 113 (12 to 17), to ground at the lower contact of cam 113. The sequence switch now advances into position 18 in which position the district selector is restored in the manner fully set forth in the 100 aforesaid patent to F. A. Stearn. It may be noted at this point that when the sender 101 completed the transmission of code impulses for setting the indicators of Fig. 3 it became disassociated from the trunk 104 and the sequence switch 110 was advanced from the selection-beyond position 11 and came to rest in position 12. 115

As soon as sequence switch 110 leaves position 16½, the holding circuit previously traced over brush 111 and terminal 107 for relays 124 and 202 is opened at the upper right contact of cam 113 and these relays thereupon release. Relay 124, upon releasing its armatures opens the circuit previously traced for relays 117 and 200, and relay 202, upon releasing, opens the circuits of relays 203 and 208. With relays 202 and 208 deenergized, holding ground is removed from conductors 209 and 216, releasing all 125 130

of the relays of Figs. 2 and 3 which are at the time operated. Upon the release of relays 324 and 328, the circuit for stations lamps 329 is opened and these lamps are extinguished.

As soon as relay 203 releases its armatures, ground is connected at the back contacts of its armatures to conductors 204, 205, 206 and 207 extending to the upper left contacts of 10 cams corresponding to cam 412 of the sequence switches associated with the indicators. The circuit for sequence switch 410 corresponding to sequence switch 300 associated with the thousands indicator may, for 15 example, be traced from battery, through the magnet winding of switch 410, the upper left contact of cam 412 (2 to 18), conductor 207 to ground at the intermediate right armature and back contact of relay 203. Since these cam contacts are closed from positions 2 to 18, inclusive, the sequence switches are advanced from whatever positions they are standing in, into their normal positions. As the sequence 25 switches reach their normal positions, the lighted lamps of the several indicators are extinguished. All apparatus employed in making the test has now been restored to its normal condition and the operator may then 30 proceed, if she wishes, to test her position with other line designations, in the manner just described.

The talking test of a "B" operator's position is conducted in much the same manner 35 as hereinbefore described, except that before starting the test, the cordless "B" operator assigns a trunk, such, for example, as trunk 104, extending to a particular manual office and directs the "A" operator at such manual 40 office to connect one of her cord circuits therewith. In response to the recording of a desired line designation upon the keyboard 100 at the "B" operator's position, the line designation becomes displayed in the manner 45 previously described upon the test indicators of Fig. 3. As soon as the operator notes the displayed number, she connects her headset 134 to the test trunk 112 by means of the multiple plugs 135 and 136 and the jacks 50 137 and 138. A circuit is now established for relay 139 which may be traced from battery through this relay, the tip of jack 137, tip of plug 135, the transmitter of the headset 134, tip of plug 136, tip of jack 138, the 55 right windings of repeating coil 142 in parallel to ground.

With relay 139 energized, a circuit is established for the reversing relay 116 extending from battery through the winding of relay 116 to ground at the armature and contact of relay 139. Relay 116, upon energizing, opens the holding circuit for relays 124 and 202 at its outer left armature and back contact and at its outer right armature 60 and front contact closes a circuit for the cut-

off relay 125. The circuit for relay 125 may be traced from battery, through the winding of relay 125, the outer right armature and contact of relay 116, bank terminal 107, brush 111 to ground at the right contacts of cam 113. Relay 125, upon energizing in this circuit, locks through its inner right armature and contact directly to ground at cam 113 independently of the armature and contact of relay 116. Upon 70 the opening of the circuits of relays 124 and 202, the circuits of the test indicator are restored to normal condition and the displayed number is effaced. Relay 124, upon de-energizing, opens the circuit of relay 117 75 which disconnects the test indicator from the conductors of test trunk 112 and reconnects the windings of relay 114 to the terminals 105 and 106. With reversing relay 116 energized, battery and ground are now reversely 80 connected through the windings of relay 114 to bank terminals 105 and 106 for supervisory purposes and in the manner fully set forth in the aforesaid patent to F. A. Stearn.

The "A" operator at the distant manual office receives a supervisory signal indicating that she may talk with the "B" cordless operator. The talking circuit extending from the headset 134 at the cordless position to the "A" operator's position may be traced 90 in part from the tip of jack 140, the upper contacts of cam 143, brush 108, bank terminal 105, the upper armature and back contact of relay 117, the upper left winding of repeating coil 142, sleeve of jack 138, sleeve 100 of plug 136, the receiver of the headset 134, sleeve of plug 135, sleeve of jack 137, the lower armature and back contact of relay 117, bank terminal 106, brush 109, the upper contact of cam 123 to the ring conductor of jack 140.

Upon the termination of the talking test, the cordless or "B" operator removes the plugs 135 and 136 from the jacks 137 and 138 thereby releasing relay 139, which, in turn, 110 releases relay 116. Relay 116 now reverses the battery and ground connections through the windings of relay 114 whereupon the "A" operator receives a disconnect signal in the well-known manner. When the "A" operator disconnects her cord from the jack 140, the circuit through the windings of relay 141 and through the windings of relay 114 is opened and relay 141 cuts the display of a disconnect signal before the "B" 115 operator in the well-known manner. The "B" operator now depresses the disconnect key 130 and releases the apparatus at her position in the manner previously described. When sequence switch 110 leaves position 125 16½ ground potential is removed at the upper right contact of cam 113 from the holding circuit of relay 125 whereupon this relay becomes released. All apparatus involved in conducting the test is now in its 130

normal position. The cordless "B" operator may conduct similar tests with other trunk circuits similar to 104 extending to other manual offices in the manner previously described.

While in the foregoing, the invention has been described as particularly designed for use in testing apparatus at a cordless "B" operator's position in a machine switching office, it will be apparent that the indicators might be employed for displaying line designations before operators in manual offices for the purpose of enabling manual operators to complete calls incoming from machine switching offices.

What is claimed is:

1. In a telephone exchange system, a trunk line, means for impressing current impulses of various characteristics upon the conductors of said trunk line, a primary register, means responsive to said impulses for variably setting said register, a secondary register, means for setting said secondary register in accordance with the setting of said primary register, an indicator positioned to be observable from the point where said impulses are impressed, and means including said secondary register for variably operating said indicator.
2. In a telephone exchange system, a trunk line, means for impressing impulses of current differing in polarity and strength upon the conductors of said trunk line, a primary register, means responsive to said impulses for variably setting said register, a secondary register, means for setting said secondary register in accordance with the setting of said primary register, an indicator positioned to be observable from the point where said impulses are impressed, and means including said secondary register for variably operating said indicator.
3. In a telephone exchange system, a trunk line, means for impressing current impulses of various characteristics upon the conductors of said trunk line, a plurality of register relays, means responsive to said impulses for operating said relays in varying combinations, a secondary register, means controlled by said relays for variably setting said secondary register, an indicator positioned to be observable from the point where said impulses are impressed, and means including said secondary register for variably operating said indicator.
4. In a telephone exchange system, a trunk line, means for impressing current impulses of various characteristics upon the conductors of said trunk line, a plurality of register relays, means responsive to said impulses for operating said relays in varying combinations, a rotatable switch, means controlled by said relays for variably positioning said switch, an indicator positioned to be observable from the point where said im-

pulses are impressed, and means including said switch for variably operating said indicator.

5. In a telephone exchange system, a trunk line, means for impressing current impulses of various characteristics upon the conductors of said trunk line, a primary register, means responsive to said impulses for variably setting said register, a secondary register, means for setting said secondary register in accordance with the setting of said primary register, an indicator comprising a plurality of groups of signals grouped to form numerals, an actuating circuit for each of said groups of signals, and means controlled by said secondary register for establishing said circuits in various combinations to display a plurality of different numerals.

6. In a telephone exchange system, a trunk line, means for impressing current impulses of various characteristics upon the conductors of said trunk line, a primary register, means responsive to said impulses for variably setting said register, a secondary register, means for setting said secondary register in accordance with the setting of said primary register, an indicator comprising a plurality of groups of signals grouped to form numerals, an actuating circuit for each of said groups of signals, and means controlled by said secondary register for establishing said circuits in various combinations to display a plurality of different numerals larger in number than the number of said groups of signals.

7. In a telephone exchange system, a trunk line, means for impressing current impulses of various characteristics upon the conductors of said trunk line, a plurality of register relays, means responsive to said impulses for operating said relays in varying combinations, a secondary register, means controlled by said relays for variably setting said secondary register, an indicator comprising a plurality of groups of signals, an actuating circuit for each of said groups of signals grouped to form numerals, and means controlled by said secondary register for establishing said circuits in various combinations to display a plurality of different numerals.

8. In a telephone exchange system, a trunk line, means for impressing current impulses of various characteristics upon the conductors of said trunk line, a plurality of register relays, means responsive to said impulses for operating said relays in varying combinations, a rotatable switch, means controlled by said relays for variably positioning said switch, an indicator comprising a plurality of groups of signals grouped to form numerals, an actuating circuit for each of said groups of signals, and means controlled by said switch for establishing said

circuits in various combinations to display a plurality of different numerals.

9. In a telephone exchange system, a trunk line, means for impressing current impulses of various characteristics upon the conductors of said trunk line, a primary register, means responsive to said impulses for variably setting said register, a secondary register, means for setting said secondary register in accordance with the setting of said primary register, an indicator comprising seven groups of signals arranged substantially in the form of the numeral eight, an actuating circuit for each of said groups of signals, and means controlled by said secondary register for establishing said circuits in various combinations to display any one of ten different numerals.

10. In a telephone exchange system, a trunk line, means for impressing current impulses of various characteristics upon the conductors of said trunk line, a plurality of register relays, means responsive to said impulses for operating said relays in varying combinations, a sequence switch register, means controlled by said relays for variably positioning said sequence switch register, an indicator comprising seven groups of signals arranged substantially in the form of the numeral eight, an actuating circuit for each of said groups of signals, and means controlled by said sequence switch register in the several positions thereof for establishing said circuits in various combinations to display any one of ten different numerals.

11. In a telephone exchange system, a trunk line, means for impressing current impulses of various characteristics upon the conductors of said trunk line, primary registers, means responsive to said impulses for variably setting said registers in succession, secondary registers, means for setting said secondary registers in accordance with the settings of said primary registers, a plurality of indicators positioned to be observable from the point where said impulses are impressed, and means including said secondary registers for variably operating said indicators.

12. In a telephone exchange system, a trunk line, means for impressing current impulses of various characteristics upon the conductors of said trunk line, a plurality of groups of register relays, means responsive to said impulses for successively operating the relays of each group in varying combinations, a rotatable switch individual to each group of relays, means controlled by the relays of a group for variably positioning the corresponding switch, an indicator associated with each switch comprising a plurality of groups of signals grouped to form numerals, and an actuating circuit for each of said groups of signals, and means controlled by each of said switches for estab-

lishing the circuits of the corresponding indicator signals in various combinations to display a plurality of different numerals larger in number than the number of said groups of signals.

13. In a telephone exchange system, an operator's position, a keyboard and an impulse sending device thereat, a trunk line, means for connecting said operator's apparatus to said trunk line, means controlled by said sending device for transmitting impulses over said trunk line in accordance with the several digits of a line designation recorded upon said keyboard, primary registers, means responsive to said impulses for variably setting said registers in succession to register the digits of said line designation, a plurality of secondary registers equal in number to said primary registers and operable in accordance with the settings thereof, an indicator associated with each of said secondary registers, each comprising a plurality of groups of signals grouped to form numerals and an actuating circuit for each of said groups of signals, and means controlled by each of said secondary registers for establishing the circuits of the corresponding indicator signals in various combinations whereby the several digits of said line designation are displayed.

14. In a telephone exchange system, an operator's position having apparatus to be tested comprising a keyboard and a sending device, an indicating device observable from said position, a trunk line extending to said indicating device, means responsive to the operation of certain keys of said keyboard for associating the apparatus of said position with said trunk line, means controlled by said sending device for transmitting impulses over said trunk line in accordance with the several digits of a line designation recorded upon said keyboard, primary registers associated with said indicating device responsive in succession to said impulses, a plurality of secondary registers equal in number to said primary registers and operable in accordance with the settings thereof, and means for displaying upon said indicating device the digits of a line designation registered by said secondary registers.

15. In a telephone exchange system, a plurality of operators' positions having apparatus to be tested, the apparatus at each such position comprising a keyboard and a sending device, an indicating device observable from all of said positions, a trunk line extending to said indicating device, means responsive to the operation of certain keys of the keyboard of the position for associating the apparatus of said position with said trunk line, means controlled by said sending device for transmitting impulses over said trunk line in accordance with the several digits of a line designation recorded

- upon said keyboard, primary registers associated with said indicating device responsive in succession to said impulses, a plurality of secondary registers equal in number to said primary registers and operable in accordance with the settings thereof, and means for displaying upon said indicator the digits of a line designation registered by said secondary registers.
- 5 16. In a telephone exchange system, an operator's position having apparatus to be tested comprising a keyboard and a sending device, a manual office, a trunk circuit extending from said office to said operator's 10 position, means for associating said trunk circuit with said apparatus, an indicating device, means under the control of said keyboard and sending device for extending a connection from said trunk circuit to said 15 indicating device, means under the control of said sending device for displaying the designation of a line recorded upon said keyboard, an operator's head set at said position, means for connecting said set with 20 said trunk circuit for completing a talking 25
- connection with said manual office, and means operable thereupon for releasing said indicator.
17. In a telephone exchange system, an operator's position, responsive means at a distant point, an indicator observable from said position controllable by said responsive means, and controlling means at said position for controlling said responsive means to cause the display upon said indicator of any desired line designation. 30
18. In a telephone exchange system, an operator's position, controlling means at said position, a plurality of trunk circuits outgoing from said position, indicating apparatus at a distant point controllable by said means over certain of said trunk circuits, and an indicator observable from said position controllable by said means over another of said trunk circuits. 35 40 45

In witness whereof I hereunto subscribe my name this 26th day of December A. D. 1922.

FRANK N. REEVES.
